MEANS FOR GATHERING OR PLEATING
TEXTILE AND LIKE MATERIALGabriel Christiaan Erasmus Keet, Johannesburg,
Transvaal, Union of South AfricaApplication February 1, 1939, Serial No. 254,614
In the Union of South Africa November 24, 1938

2 Claims. (Cl. 112—175)

The present invention consists of means for gathering or pleating cloth or textile and like materials preparatory to smocking the same.

Gathering preparatory to smocking is at present usually done by hand and this is a long and tedious operation, and the object of the present invention is to devise a simple means or machine which will accomplish the gathering or pleating quickly, accurately and effectively.

According to the invention the means or machine includes a pair of rotated meshing toothed wheels between which the material is passed, and which impart the requisite folding for the gathering or pleating thereto, and one or a plurality of threaded needles adapted to pass through the folded material to retain the folded formation.

The wheels are grooved or recessed peripherally or circumferentially to provide one or a plurality of openings or spaces in and between the wheels, in each of which openings or spaces the end portion of a needle or needles can be arranged. If a plurality of the corresponding peripheral grooves be provided they may be formed at regular or irregular intervals in the wheels as desired. In a practical form of the invention the grooves or recesses in the one toothed wheel extend to the root circle of the teeth, and those in the other wheel are only deep enough to accommodate the end portions of the needles.

The toothed wheels may each be constructed as a single wheel and have the circumferential grooves or recesses formed or cut therein, or they may be constructed in sections or be built up of a number of narrow wheels having their teeth aligned and fashioned at the sides to form or leave the grooves or recesses.

Means are provided for moving the one wheel away from the other, either to insert the material to be gathered, or remove it, or to adjust the one wheel in relation to the other to adapt them to different thicknesses of material, or to vary the width of the pleats or folds. These means consist in rotatably carrying the one wheel in a hinged or pivoted bridle or frame so that it may be raised from and lowered on to the other, and providing means for fixing the bridle when the wheels are in full mesh or in any adjusted position.

Means are provided at a suitable distance from the wheels for carrying or supporting the needle or needles which take or collect the folded material and pass through it the gathering thread or threads by means of which the folded or pleated formation obtained by the meshing toothed wheels is retained.

The means for carrying or supporting the needles is made movable by pivoting it, so that the end portions of the needles can be adjusted in the openings or spaces, or moved therefrom to permit the gathered material to be removed from the needles. Provision is made for fixing the needle carrier in any adjusted position of the needles.

The invention will be more fully explained with the aid of the accompanying drawings, wherein—

Fig. 1 is a front elevation of the means or machine.

Fig. 2 is a plan of Fig. 1.

Fig. 3 is a sectional side elevation of Fig. 1 on line x—x.

Fig. 4 is a side elevation of the means or machine showing the bridle or member carrying the upper toothed wheel moved to raise the wheel, and the needle carrier rotated to raise the needles.

Referring now to the drawings in which a practical embodiment of the invention is illustrated, 1 denotes the one and upper toothed wheel, and 2 the other and lower toothed wheel adapted to mesh with the wheel 1 to impart the folding for the gathering or pleating of the material which passes between the wheels. The teeth of the wheels 1, 2, are preferably narrow at the edges or formed with comparatively sharp outer edges, as shown, and when meshing allow sufficient clearance between them to permit of the passage of the textile material between them without cutting or damaging the same.

The wheels 1, 2, are rotatably arranged in a frame or framework 3, shown of shallow U shape in cross-section, or provided with a base portion 4 and upright sides 5, 6.

The wheel 2 is built up of a number of separate sections or small wheels 2a, arranged with their teeth aligned upon the squared central portion of a shaft or spindle 7. The shaft 7 is reduced in diameter at its outer ends and said end portions 8 are shown journalled in open-ended bearings 9, 10, which are formed out of the base 4 of the frame 3 by cutting the same and bending up the portions 11, 12. This construction leaves spaces between the portions 11, 12, and the sides 5, 6, of the frame 3 to accommodate surplus material at the sides of the material being gathered.

The wheel 1 is rotatably mounted, through the medium of its shaft or spindle 13, in a U-shaped member or bridle 14, which is pivotally attached at its outer ends by bolts 15, 16, to the sides 5, 6, respectively of the frame 3, at the front and near the top. The wheel 1, as shown, is built up of a

number of separate sections or small wheels $1a$ arranged, with their teeth aligned, upon the squared central portion of the shaft or spindle 13 , between collars or washers $17, 18$. The collars or washers $17, 18$, are placed next stop pins $19, 20$, passing through the squared portion of the shaft 13 , and a coiled spring 21 is interposed between the collar or washer 17 and the adjacent wheel section $1a$, to keep the wheel sections $1a$ in proper position. The shaft or spindle 13 is made cylindrical near the ends at 22 and 23 , and beyond said portions $22, 23$, is reduced in diameter at $24, 25$, respectively, and journalled in holes or bearings in the bridle 14 . Beyond the cylindrical portion 24 the shaft 13 is formed with a squared portion 26 upon which is fixed a handle 27 for turning the wheel 1 and through it the meshing wheel 2 ; 28 being a screw screwed into the end of the shaft 13 for securing the handle 27 on the squared portion 26 thereof.

The inner portion 29 of the bridle 14 , near the sides thereof, is adapted to enter slots $30, 31$, formed in the vertical sides $5, 6$, of the frame 3 , and to rest on the frame 3 at the bottom of the slots $30, 31$, when the wheels $1, 2$, are fully in mesh. Open-ended slots $32, 33$, formed in the underside of the bridle 14 pass over studs $34, 35$, screwed in the sides $5, 6$, of the frame 3 , and wing nuts $36, 37$, on said studs $34, 35$, serve for fixing the bridle 14 to the sides $5, 6$, of the frame 3 when said bridle 14 is in its lowermost position, or when it is slightly raised to adapt the means or machine to thicker material or vary the width of the gathering of the material. Open-ended slots $38, 39$, are formed in the sides $5, 6$, of the frame 3 to provide clearance for the cylindrical portions $22, 23$, of the shaft 13 when the bridle 14 is lowered to bring the wheel 1 into mesh with the wheel 2 .

In the form shown in the drawings circumferential or peripheral grooves or recesses 40 are provided at regular intervals in the wheel 1 , extending inwardly to the roots of the teeth of said wheel 1 , and shallower correspondingly positioned circumferential or peripheral grooves or recesses 41 are provided in the wheel 2 . The grooves 40 and 41 in the wheels 1 and 2 respectively form the openings or spaces 42 in which the sharpened end portions of the needles 43 are arranged. The shallow grooves 41 in the wheel 2 are rounded at the bottom and are only deep enough to accommodate the needle end portions, so that the teeth of said wheel 2 act, if necessary, to support the needle ends against springing downwardly and ensure that the needles will pass through the pleated material near the upper edges of the pleats. The grooves or recesses 40 are formed by constructing each of the wheel sections $1a$ with a spacing boss 44 , and the grooves or recesses 41 are made by grooving or shaping the side edges of the teeth of the wheel sections $2a$ to the requisite depth. $43a$ is the thread.

45 represents the needle carrier or means for holding the needles 43 . The needles are shown of the ordinary sewing machine type with the eye at the piercing or sharpened end, and are adapted to be held at the other and enlarged rear end 46 , for which purpose they are rounded on the underside and provided at the top with the flattened surfaces 47 , see Fig. 3. The carrier 45 includes a lower member or bar 48 provided with grooves 49 in which the rounded surfaces of the enlarged rear ends 46 of the needles 43 are arranged, and a shorter upper member or bar 50

adapted to clamp the needles 43 in the grooves 49 by engaging the flattened surfaces 47 thereof. 51 are clamping thumbscrews which pass through holes in the upper member or bar 50 and engage in screw-threaded holes in the lower member or bar 48 and act to press the bar 50 on to the needles to clamp them. The lower member or bar 48 is provided at the ends with trunnions $52, 53$, which are journalled in open bearings or slots $54, 55$, respectively in the sides $5, 6$, of the frame 3 . The trunnion 52 is provided with a reduced squared extension 56 upon which is arranged a lever or handle 57 for rotating the needle carrier 45 in order to adjust the position of the needles 43 or raise them in order to remove the gathered material therefrom. The lever 57 can be fixed in any adjusted position of the needle carrier 45 , and for this purpose is provided with an open-ended slot 58 in which engages a stud 59 screwed in the side 5 of the frame 3 and fitted with a wing-nut 60 which is adapted to clamp the lever 57 against said side 5 .

Further open bearings or slots $61, 62$, for the trunnions $52, 53$, and a screwed hole 63 for the stud 59 are shown provided in the frame 3 to allow of the needle carrier 45 being placed further back in the frame 3 to permit of longer needles 43 being used.

In the operation of the machine, in inserting the material to be gathered, I prefer to raise the upper wheel 1 in its bridle 14 and lay the material on the lower wheel 2 in front of the horizontally arranged threaded needles 43 . The bridle 14 is then lowered to cause the wheel 1 to mesh with the wheel 2 , and fixed in position by the wing nuts $36, 37$. Upon rotation of the handle 27 the material passes through and is folded by the meshing wheels $1, 2$, and is pierced by and fed or pressed on to the threaded needles 43 . When all the material to be gathered, or sufficient of it to fill the needles 43 , has been folded and passed on to the needles 43 , the wing nuts $36, 37$, are loosened and the bridle 14 raised to move the wheel 1 from the wheel 2 . The wing nut 60 is then loosened and the lever 57 rotated—see Fig. 4—to move the needle carrier 45 about its trunnions $52, 53$, and raise the needles 43 so that the gathered material can be removed therefrom together with the gathering threads.

The sectional construction of the wheels $1, 2$, permits of sections $1a, 2a$, of different widths being used in conjunction with a correspondingly grooved needle carrier 45 , to vary the distance between the gathering threads as desired.

What I claim as my invention and desire to protect by Letters Patent is:

1. Means for gathering or pleating textile and like material, including a frame, a pair of rotatable meshing toothed wheels arranged one above the other between which the material is passed and by which it is pleated, the lower wheel being rotatably mounted in the frame, the wheels being constructed with a plurality of circumferential aligned grooves forming openings between them, a U-shaped bridle pivoted to the frame in front of the wheels and rotatably carrying the upper wheel so that the latter can be moved away from the lower wheel, a threaded needle arranged in each of said openings in the wheels which openings receive the needles in the operative position thereof the pointed end portion of which needle lies between the wheels, a needle carrier constructed in two parts between which the needles are clamped, said needle car-

rier being pivoted so that the points of the needles can be lifted out of the openings in the lower wheel after the upper wheel has been raised, and means for fixing said pivoted needle carrier when the points of the needles are in the openings, as set forth.

2. Means for gathering or pleating textile and like material, including a frame, a pair of rotatable meshing toothed wheels arranged one above the other, the lower wheel being rotatably mounted in the frame, the wheels being constructed with a plurality of circumferential aligned grooves forming openings between them, a U-shaped bridle pivoted to the frame in front of the wheels and rotatably carrying the upper wheel so that the latter can be raised from

the lower wheel, means for fixing said bridle to the frame when the wheels are meshing, a threaded needle arranged in each of said openings in the wheels which openings receive the needles in the operative position thereof the pointed end portion of which needle lies between the wheels, a needle carrier constructed in two parts between which the needles are clamped, said carrier being pivoted so that the points of the needles can be lifted out of the openings in the lower wheel after the upper wheel has been raised, and means for fixing said pivoted needle carrier to the frame when the points of the needles are in the openings, as set forth.

10 15 GABRIEL CHRISTIAAN ERASMUS KEET.
